UNITED STATES PATENT OFFICE.

LESLIE M. SHERIDAN, OF EL PASO, TEXAS.

ENGINE.

1,302,442.

Specification of Letters Patent. Patented Apr. 29, 1919.

Application filed May 18, 1917. Serial No. 169,551.

To all whom it may concern:

Be it known that I, LESLIE M. SHERIDAN, a citizen of the United States, residing at El Paso, in the county of El Paso and State 5 of Texas, have invented a new and useful Engine, of which the following is a specification.

The device forming the subject matter of this application is adapted to be employed 10 as a rotary engine, as a pump for liquids, as an air compressor, as a vacuum pump, and for other purposes, but for convenience in description, it will be presupposed that the structure is employed as a rotary engine.

15 One object of the invention is to provide novel means whereby a rotary shaft and a piston are coupled together operatively, the piston having right-line sliding movement in a rotor, which, in its turn, rotates in a 20 stator.

A further object of the invention is to improve structurally, and in details which will be pointed out hereinafter, the elements above enumerated.

25 A further object of the invention is to provide means for cooling the internal working parts of the engine by means of a lubricant which is pumped to said parts, as hereinafter described.

30 With the above and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

40 In the accompanying drawings:—

Figure 1 shows in side elevation, a rotary engine embodying the present invention;

Fig. 2 is a section taken approximately on the line 2—2 of Fig. 1;

45 Fig. 3 is a vertical longitudinal section taken through an engine embodying the present invention;

Fig. 4 is a horizontal section of the engine;

50 Fig. 5 is a sectional detail showing a portion of the piston; and

Fig. 6 is a fragmental perspective showing a portion of the rotor.

The engine herein disclosed consists of a 55 stator, including an annular body or ring

6 disposed between end walls 4 and 5, and held therebetween. Side plates 7 coöperate with the end walls 4 and 5 to define water jackets 8. The body or ring 6 of the stator is circumscribed by a band 9, which, co-operating with the body 6, forms a water jacket 10. The band 9 carries suitable connections 11 constituting, respectively, an inlet and an outlet for the water jacket 10. It is obvious, however, that the water jacket 60 spaces may be formed integrally with the parts wherewith they coöperate, in accordance with the common practice in gas engine design.

The end walls 4 and 5 of the stator are 70 supplied with bearings 12 in which is journaled a shaft 14. A hood 16 coacts with the end wall 5 to form a compartment in which certain operating mechanisms to be described hereinafter are housed. A fly 75 wheel 17 may be secured to one end of the shaft 14, but the fly wheel may be omitted, if desired, since the rotor (hereinafter described) may take the place of a fly wheel, and render the part 17 unnecessary. 80 The shaft 14 may be provided with the usual starting crank 18. The shaft 14 is provided with a rectangular intermediate part 19 located within the contour of the stator.

The numeral 20 denotes a piston which is 85 of approximately rectangular contour, the piston being supplied with a rectangular opening 21 in which the rectangular part 19 of the shaft 14 is slidably received. The piston is provided with compartments 100 90 located on opposite sides of the opening 21, there being lubricant ports 102 forming communications between the compartments 100 and the opening 21. The piston 20 is provided with parallel ends 22. The piston 95 20 is surrounded by packing rings 23 pressed outwardly by springs 24 so as to provide fluid-tight joints between the piston 20 and the walls 4 and 5 of the stator, and between the ends 22 of the piston and the parallel 100 walls 25 of an opening 36 formed in a rotor 26.

The rotor 26 is mounted to turn in the body or ring 6 of the stator, between the end walls 4 and 5 of the stator, and comprises opposed parts 27 which may be tongue and grooved together as shown at 28, the inner edges of the parts 27 of the rotor being supplied with coöoperating grooves 29 receiving a packing 30. In the inner faces 110

of the parts 27 of the rotor 26, recesses 31 are formed, these recesses receiving compression springs 32 which tend to press the parts 27 of the rotor 26 outwardly in opposite directions, so that the rotor will coöperate with the walls 4 and 5 of the stator. The end wall 4 is provided with oil ports 33, communicating with pipes 35, to the end that all movable internal parts of the device 10 may be lubricated and cooled, as herein-after described.

The end wall 5 has an intake port 35 which is adapted to communicate, at times, with the chamber 36 of the rotor 26. The 15 intake port 35 is controlled by an inwardly opening valve 37 having a stem 38 mounted in the part 35. A spring 39 coöperates with the stem 38 on the valve 37, to hold the same normally closed. The valve 37 is adapted 20 to be opened by a lever 40, coöperating at one end with the stem 38, and fulcrumed on a bracket 41 carried by the end wall 5. The end wall 5 is provided with an exhaust port 42 controlled by an outwardly closing valve 25 43 including a stem 44 mounted to slide in the port 42, the valve 43 being constrained to a closed position by means of a spring 45 coöperating with the stem 44. The valve 43 is opened by a lever 46 coacting with a 30 stem 44, the lever 46 being fulcrumed on a bracket 47 carried by the end wall 5. The inner ends of the levers 46 and 40 carry rollers 48 or other suitable elements coöperating with a cam groove 49 fashioned in 35 the hub 50 of a gear wheel 51 carried by a stub shaft 52 mounted on the end wall 5. The gear wheel 51 meshes into a pinion 53 secured to the shaft 14.

The numeral 72 denotes a spark plug ordinarily carried by one of the end walls 4 or 5 of the stator and so located that it may coöperate with the chamber 36 in the rotor 26. For convenience in describing the operation of the structure, that portion of the 40 chamber 36 which lies above the piston 20 in Fig. 3 may be described as constituting a compartment 70, that portion of the chamber 36 which lies below the piston 20 in Fig. 3 constituting a compartment 71.

Suppose that the parts are arranged as shown in Fig. 3. Then the piston 20 is at the limit of its upward stroke. The compartment 70 has been reduced to its smallest capacity, and a charge has been compressed 50 in the compartment 70. The charge is fired in the compartment 70 by the spark plug 72. Now there occurs an operation which will be denominated as operation A. The expanding charge in the compartment 70 causes the piston 20 to slide on the rectangular part 19 of the shaft 14, and at the same time, rotation is imparted to the shaft 14. The piston slides in the chamber 36 of the eccentrically mounted rotor 26, and the 55 rotor turns in the stator, it being observed at

this point that the axis of the shaft 14 is not concentric with the axis of the rotor. By the time that the rotor 26 has turned through 180 degrees, the compartment 70 has attained a maximum size, the piston 20 70 being at the limit of its downward stroke, which is a power stroke.

There now occurs an operation which will be called operation B, during which the shaft 14 turns through 180 degrees, the piston 20 returning to the position of Fig. 3, the compartment 70 being reduced to its smallest capacity, and the exploded charge being secured out of the compartment 70. 75

During operation C, the shaft 14 turns 80 through 180 degrees, and the piston 20 moves downwardly from the position shown in Fig. 3, the compartment 70 attaining a maximum capacity, and a fresh charge being sucked into the compartment 70. 85

During operation D, the shaft 14 turns 90 through 180 degrees, and the piston 20 moves upwardly into the position of Fig. 3, the first charge being compressed in the compartment 70. 90

During operation A, the compartment 71 is reduced to a minimum size and the exploded charge in the compartment 71 is scoured out. During operation B, the compartment 71 attains a maximum size, and a 95 fresh charge is sucked thereinto. During operation C, the compartment 71 is reduced to a minimum size, and the charge therein is compressed. During operation D, the charge in the compartment 71 expands, and 100 the compartment 71 attains a maximum size.

By forming the cam groove 49 properly in the hub 50 of the gear wheel 51, and by properly proportioning the relative diameters of the gear wheel 51 and the pinion 53, 105 the valves 37 and 43 will be so timed as to open and close in such a manner as to render the foregoing operations denoted as A, B, C and D possible.

It will be seen readily that when the piston 20 moves on the squared portion 19 of the shaft, oil will be admitted by the ports 33 into the opening 21 and, through the ports 102 and the compartments 100, a thorough and adequate circulation will be effected, the 110 part 19 of the shaft exerting an important pumping action, and all working parts of the engine being properly lubricated and cooled. 115

When acting as a steam engine, the timing 120 gears and cam-actuated intake and exhaust valves are removed, and the cycle of operation is as follows:

Steam is admitted through the port 35, and the pressure moment upon the shaft 125 axis causes the piston, the shaft and the rotor to revolve until the intake opening is covered. The expansion of the steam causes a continued rotation until one-half revolution has been made when the exhaust passage 130

42 is uncovered, and the expanded steam is forced out. At another half revolution, the intake passage is uncovered and the cycle of operations is repeated.

5 In acting as a vacuum pump, a compressor, or a pump for liquids, the cycle of operations is as follows: The gas or liquid is drawn through the opening or port 35. This port is located in such a way as to remain 10 uncovered for practically half a revolution. During the other half revolution, the discharge port 42 is uncovered and the gas or liquid is discharged into the vessel provided for receiving it.

15 Having thus described the invention, what is claimed is:—

1. In a device of the class described, a stator; a rotor journaled in the stator and provided with a chamber having parallel 20 edges; a piston in the chamber of the rotor and guided for right line movement therein by the parallel edges of the chamber, the piston being equipped with an opening having parallel sides; a shaft journaled eccentrically in the stator and including an intermediate portion received in the opening of the piston, the intermediate portion of the shaft having parallel edges coöperating with the parallel sides of the opening in the piston 25 to guide the piston for right line movement transversely of the shaft; an inlet and an outlet carried by the stator and communicat-

ing with the chamber of the rotor when the rotor is rotated; valves controlling the inlet and the outlet; and shaft-actuated means co- 35 operating with the valves to open and close the same.

2. In a device of the class described, a stator; a rotor journaled in the stator and provided with a chamber having parallel 40 edges; a piston guided for right line movement by the parallel edges of the chamber in the rotor, the piston having an opening including parallel sides, and being provided with chambers disposed on opposite sides of 45 the opening, there being lubricant ports in the piston forming communications between the opening of the piston and the chambers thereof, the stator having lubricant ports communicating at times with the opening in 50 the piston; and a shaft journaled eccentrically in the stator and including an intermediate portion received in the opening of the piston and having parallel faces coöperating with the parallel sides of the opening in the 55 piston to guide the piston to right line movement transversely of the shaft.

In testimony that I claim the foregoing as my own, I have hereto affixed my signature in the presence of two witnesses.

LESLIE M. SHERIDAN.
